(57) **CLAIM**

The ornamental design for a hammer mill with dosing device, as shown and described.

DESCRIPTION

FIG. 1 is a perspective view of a hammer mill with dosing device, showing my new design from the front, top and right side;

FIG. 2 is a front elevational view thereof;

FIG. 3 is a rear elevational view thereof;

FIG. 4 is a right side view thereof;

FIG. 5 is a left side view thereof;

FIG. 6 is a bottom plan view thereof; and,

FIG. 7 is a top plan view thereof.

The broken lines in the drawings depict unclaimed environmental subject matter.
